UNITED STATES PATENT OFFICE

2,595,919

REMOTE-CONTROL SYSTEM EMPLOYING A
THERMAL DELAY SWITCHJoseph L. Bonanno, Madison, N. J., assignor to
The Lionel Corporation, New York, N. Y., a cor-
poration of New York

Application November 12, 1947, Serial No. 785,407

3 Claims. (Cl. 104—150)

1

The present invention relates to remote control systems employing thermal delay switches and is more particularly directed toward such switches and circuits suitable for use in the operation of toy railroad cars.

It is customary to provide toy railroad cars with an instantaneously operated device such as an electromagnetically operated coupler and with some other electrically operated accessories such as dump car mechanism, door opening mechanism, merchandise handling mechanism or the like operated less frequently, or subsequently. See, for example, my Patent No. 2,232,508, February 18, 1941. The present invention aims to provide an arrangement whereby the couplers may be actuated when desired and whereby the other accessories may be actuated after the couplers have been actuated, the controls requiring no more than the usual power and return rails which carry the propulsion current for the toy railroad trains.

According to the present invention the car carries a relay which is not responsive to propulsion current but is responsive to non-propulsion current in the rails. This non-propulsion current may be a tuned radio frequency current, produced as shown in my application Serial No. 779,273, filed October 11, 1947, or a direct current component superimposed upon the A. C. propulsion current. A relay operated in such superimposed current is shown in my Patent No. 2,155,343, dated April 18, 1939.

The present invention makes it possible to control the couplers or the accessory as desired when the car is at any place along the usual two rail or three rail track.

Other and further objects will appear as the description proceeds.

The accompanying drawings show, for purposes of illustrating the present invention, one form, together with modified forms of circuit, it being understood that the drawings are illustrative of the invention rather than limiting the same.

In these figures:

Figure 1 is a perspective view of a thermal delay switch together with wiring diagram;

Figure 2 is a cross-sectional view on the line 2—2 of Figure 1;

Figure 3 is an end view taken from the right of Figure 2;

Figure 4 is an exploded view showing the component parts;

Figure 5 illustrates a modified wiring diagram; and

Figure 6 shows a complete wiring diagram for

2

a radio frequency control and part of the car.

The thermal delay switch has an insulating base 10 having a threaded hole 11, two notches 12, 12, and two holes 13, 13. Immediately above this base is a bimetallic thermal element 15 of U-shape. This thermal element has two contact terminals 16, 17 which protrude beyond the base, two holes 18, 18 spaced the same as the holes 13, 13, and its left end as shown in the drawings 10 is entirely free. This bimetallic element is so arranged that its free end bends upwardly away from the base upon heating of the bimetallic element by currents flowing through it.

Immediately above the bimetallic element 15 15 is a spacer 19, made of insulating material and above this spacer is a sheet of insulating paper 20 and a flexible sheet metal contact plate 21. The contact plate, insulating sheet and thermal element all have the same general contour and 20 are provided with holes which align with the holes 13. The free end of the contact plate 21 carries a silver contact 24. Immediately above the contact plate 21 is another spacer 25 similar to the spacer 19. A cover plate 26 has stiffening 25 side flanges 27, 27 and prongs 28 adapted to enter the notches 12 and be bent about the bottom of the base. The plate 26 has holes 29 adapted to be aligned with similar plate holes in the other parts, and hollow rivets 30, 30 and spacers 31, 31 are employed to assemble the other parts together. The contact plate 26 has a bendable tongue 32 carrying a silver contact 33 opposite the contact 24 of the flexible plate 21. The tongue 32 is adapted to be bent to adjusted position by a screw 34 passing through the threaded hole 11.

The contact plate 21 has a protruding soldering lug 35 and the cover member 26 has a similar lug 36. The thermal delay switch is carried 40 on the car C, Fig. 6, and one side of the bimetallic element (for example 17) is connected by wires 37, 38 with electromagnetic couplers 39, 39 carried by the car and grounded as usual to the return rail 45. The other terminal 16 of the bimetallic element is connected by wire 40 with a contact 41 adapted to be engaged by an armature 42 of a relay 43. As shown in Figures 1 and 6, this relay is of the type adapted for use in an electronic controller and forms part of a car carried assembly R which also includes a rectifier 46 and a tuned radio frequency receiver 47. These parts are connected through the usual contact rollers 44' on the car to the power rail 44 and through the wheels 45' as usual to the 55 return rail 45.

The propulsion current circuit includes a variable voltage stepdown transformer 61 connected to the power supply wires 62 and having an output circuit whose wires 63 and 64 are connected to terminals 65 and 66 of a radio frequency transmitter designated generally by the reference character 67. This radio frequency transmitter has an output coil 68 composed of a few turns of heavy copper wire connected with the terminal 65 and with an output terminal 69. The terminal 66 of the controller 67 is connected by a strap 70 to an output terminal 70. The terminals 69 and 70 of the radio frequency transmitter are connected by wires 71 and 72 with the center and grounded rails 44 and 45 of the track layout.

The radio frequency transmitter 67 has input terminals 80 and 81 adapted to be connected to the power supply 62. The transmitter is here shown as provided with a diode-pentode vacuum tube having two filaments 83 and 84 connected between the terminals 80 and 81. The filament 83 cooperates with an anode 85 and cathode 86 of a diode section, while the filament 84 cooperates with a cathode 87 and anode 88 and two grids 89 and 90 respectively of a pentode section. The anode 85 of the diode section is connected to the filament as indicated at 91. The anode 88 of the pentode section is connected by a wire indicated at 92 with one side of a trimmer condenser 93 and with a metal plate 94 having a plurality of resilient fingers 95 adapted to be brought into engagement with contacts 96 connected to a plurality of taps carried by a tank coil 97. One end of the tank coil 97 is connected to the trimmer condenser 93 by a wire indicated at 98, while the other end of the tank coil 97 is connected through a radio frequency choke 99 and wire 100 with the cathode 96 of the diode section. Two condensers 101 and 102 are in series with one another and in parallel with the trimmer condenser. These condensers are connected to the filament circuit by a wire indicated at 103, the condenser 101 is shunted by a condenser 104 and resistance 105 connected to the control grid 90 by a wire 105'. The control grid 99 is connected to the radio frequency choke lead 106 through a resistance 106 and the cathode 87 and filament circuit through a condenser 107. A condenser 108 interconnects the filament 84 and cathode 87 with the choke lead 100. A condenser 109 is placed across the input terminals 65 and 66 to by-pass the radio frequency currents on the power side.

When the device is designed for operation on 60 cycle house current and employs a No. 117N7GT tube suitable values for the condensers, resistances, choke and tank coil may be selected whereby it is possible to secure frequencies of from 240 to 360 kilocycles to be supplied the propulsion circuit and a selected frequency in this range is available when the desired button is depressed.

The receivers such as R have wiring diagrams such as shown in Figures 1 and 6. The receiver R shown at the left end of Figure 6 responds to one selected frequency and is adapted for controlling a particular load, while the receiver R carried on the car C responds to a different frequency and is used to control the two loads through the thermal relay.

When the relay 43 closes the circuit at contact 42 current flows from the power rail directly to the contact 42 and through the wire 40 to the thermal relay parts described in detail herein. When this circuit is closed propulsion current as well as any other circuit circulates

through the load circuit of the thermal relay. The power of course comes from the power transformer 61, the electromagnetic relay acting as connecting means to the power line.

Where it is desired to employ the thermal relay in a circuit having a relay operated by superposed direct current as in my Patent No. 2,555,343, a direct current sensitive relay such as shown at 23 in that patent is used instead of the relay 43 discussed above.

When the track circuit is provided with radio frequency currents of the frequency corresponding with that of the tuned receiver the relay is actuated and current flows through the thermal element to the couplers to operate them. On heating of the thermal element it moves against the insulating sheet 20 and applies pressure to the free end of the flexible sheet 20 and applies pressure to the free end of the flexible contact plate 21 bringing the contact 24 against the contact 33. This interconnects plates 21 and 26. These plates may be employed as control switches for additional accessories. The circuit can be connected as shown in Figure 1 wherein the relay connected side 16 of the thermal element is connected to one of the soldering lugs 35 or 36 while the other lug is connected to an accessory device such as an unloading coil 50, which is grounded. It will be noted in this arrangement that the current for operating the unloading coil does not pass through the thermal element. These parts can readily be manufactured and adjusted so as to operate with rather precise timing so that when the relay receives but a short impulse of operating current the couplers only are operated and when the relay circuit is closed for a few seconds the thermal element acts to close the circuit to the other accessory.

The same structure for thermal retarder can be used as a direct thermal relay as indicated in Figure 5 in which the thermal element 15 is in a circuit entirely different from that of contact members 24' and 33'.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. A toy railroad car having two current collectors cooperable with the usual rails, a relay on the car connected to the current collectors to be energized therefrom, the relay being non-responsive to propulsion current but responsive to non-propulsion current in the rails, and a normally open work-circuit on the car closed when the relay is energized, said work circuit including two current consuming electromagnetic devices one permanently connected to the relay through a bimetallic thermal member adapted to be heated by flow of current, the other including a switch closable by the thermal member when heated, whereby one of the electromagnetic devices may be actuated by instantaneous energizing of the relay, and the other device actuated only after the relay has been energized for a predetermined time.

2. A toy railroad car as claimed in claim 1 wherein the relay connection includes a tuned radio frequency receiver and rectifier.

3. A toy railroad car having power supply and grounded current collectors cooperable with the usual rails, a pair of electromagnetically opera-

ble couplers connected to the grounded current collector, a car-carried electrically operated accessory connected to the grounded current collector, a normally open car-carried relay having one contact connected to the power supply rail, a bimetallic thermal element connected between the other contact of the relay and the couplers so that coupler operating current passes through the thermal element upon closing of the relay, and a relay connected accessory operating circuit in parallel with the thermal element and coupler and including a pair of normally open contacts closable by the thermal element.
